UNITED STATES PATENT OFFICE

FRENCH E. DENNISON, OF BELOIT, WISCONSIN, ASSIGNOR TO NATIONAL REFRIGERATION CORPORATION, OF BELOIT, WISCONSIN, A CORPORATION OF DELAWARE

REFRIGERATING APPARATUS

Application filed August 4, 1927. Serial No. 210,548.

This invention relates to refrigerating apparatus particularly of the household type and aims to improve the efficiency of refrigerators of this character.

5 In the refrigerators of the above type, such as have been used heretofore, much difficulty has been encountered in properly apportioning the cooling effect of the evaporator so as to sufficiently cool the ice making compartment and not over-cool the food compartment. Another difficulty was the fact that too great a circulation of air in the food compartments caused the food to dry up in a very short space of time. One 10 of the reasons for these difficulties was the fact that the ice compartment, food compartment and evaporator were all in direct communication, allowing too much circulation, and improperly apportioning the circulation 15 of cooling effect and also permitting a material loss in cooling effect to the ice compartment, as well as the food compartment, whenever the refrigerator door was opened to obtain access to the latter compartment.

20 It is therefore the primary object of this invention broadly stated to eliminate the most, if not all, of the circulation of air directly from the evaporating element to the food compartment.

25 It is further an object of this invention to provide a refrigerating apparatus in which the distribution of cooling effect from the evaporator is properly apportioned between the ice compartment and the cooling compartment.

30 It is also an object of this invention to provide a refrigerating apparatus employing an ice compartment which does not communicate with the cooling compartment.

35 A further object is to provide a maximum of food storage space by making the whole interior of the cabinet available for this purpose.

40 Further objects of this invention will be apparent as the same becomes better understood from an examination of the specification and claims in connection with the accompanying drawings, wherein,

45 Fig. 1 is a front elevation of a refrigerator embodying this invention;

Fig. 2 is a horizontal section taken at the line 2—2 of Fig. 1 and

Fig. 3 is a fragmentary vertical section taken at the line 3—3 of Fig. 2.

Referring to the drawings more particularly, reference character 4 indicates generally a refrigerating cabinet preferably suitable for household use. The type of cabinet illustrated includes a center mullion 5 on opposite sides of which are disposed the ordinary swinging doors 6 and 7. 55

The space closed by the doors 6 and 7 constitutes the cooling chamber. The cooling chamber is insulated from the outer walls of the cabinet by suitable insulation 8 and is in 65 two parts 9 and 11 separated by the centrally disposed evaporator compartment 12 which will presently be described.

The evaporating compartment 12 is very narrow and is situated behind the center 70 mullion 5.

Centrally located beneath the cooling compartment and surrounded by the insulated material of the cabinet is the ice compartment 13. The evaporating compartment 75 opens directly at its lower end into the top of the ice compartment 13 and includes a pair of vertical partitions 14 which are spaced from the evaporating element 15 and completely isolated from the cooling chamber. The evaporating element 15 is in the form of a thin vertical member, the lower end of which rests upon the bottom of the ice compartment with ice trays 16 and 17 on either side thereof. 80

The element 15 is supported in spaced relation to the partition 14 by screws 18 and radiating fins 19 project from opposite sides of the element 15 into proximity to but not contacting with the walls 14. 85

The ice compartment is entirely isolated and insulated from the cooling compartment and is provided with its own door 21 which may be opened when it is desired to obtain access to the ice compartment. 90

The cooling chamber comprising the parts 9 and 11 is cooled indirectly from the evaporating element 15 by radiation from the partitions 14 and since there is no direct circulation of air from the evaporating element 100

through the cooling chamber and back again to the refrigerating element, there is no tendency of the food or other substances in the cooling compartment to dry up.

5 The fact that the evaporating element 15 cools the cooling chamber only indirectly through the partitions 14 and is in direct communication with the ice compartment, the major cooling effect is provided for the 10 ice compartment which is highly desirable and just sufficient cooling effect is provided for the cooling chamber.

It will be observed that the lower end of 15 the evaporating element rests directly upon the bottom of the ice compartment. This compartment is provided with a metal lining 21 with which the element 15 is in contact so that direct heat conduction between the lowest coldest end of the element and the 20 compartment lining is established which reduces the lining to a low temperature and thereby facilitates the freezing of the ice.

While the space between the walls 14 in 25 which the evaporating element is disposed is relatively narrow it nevertheless permits a limited degree of air circulation, the coldest air next to the element dropping into the ice compartment while the warmer air will rise along the inner faces of the walls 14 thereby further increasing the refrigerating 30 effect in the ice compartment and reducing the cooling effect in the food compartment.

It will be noted that the entire storage 35 space of the cabinet is available for the storage of food products, none of this space being occupied by the ice trays and refrigerating coils as has been customary in household apparatus heretofore. A maximum of food storage space is therefore provided and in 40 addition the ice chamber is not only thoroughly insulated but it is cut off from communication with the food compartments so that the opening of the doors of the food compartments does not affect or reduce the 45 refrigeration in the ice compartment.

Below the ice compartment and insulated 50 therefrom is a refrigerating apparatus compartment which is closed by a door 22. This refrigerating apparatus may be of any suitable type comprising a motor driven air cooled compressor which is mounted within a cylindrical condenser as shown in a pending application, Serial No. 81,177 filed January 14, 1926.

55 I am aware that many changes may be made and many details of construction varied throughout a wide range without departing from the principles of this invention and I, therefore, do not wish to be limited to the details shown or described.

I claim:

1. In a refrigerating apparatus, the combination of a refrigerating cabinet provided with a cooling compartment, an evaporating element centrally disposed in said compartment,

70 ment, and partitions separating the evaporating element from the cooling compartment and forming an evaporating compartment, the cabinet being also provided with an ice compartment separated from the cooling compartment and communicating directly with the evaporating compartment.

2. In a refrigerating apparatus, the combination of a refrigerating cabinet provided with a cooling compartment, an evaporating element centrally disposed in said compartment, and partitions separating the evaporating element from the cooling compartment and forming an evaporating compartment, the cabinet being also provided with an ice compartment below the evaporating compartment and separated from the cooling compartment and communicating directly with the evaporating compartment. 75

3. A refrigerating apparatus comprising a plurality of food compartments, a separate ice compartment, a refrigerating element disposed between said food compartments separated therefrom by partitions and extending into the ice compartment, said partitions forming a chamber which communicates with the ice compartment, but not with the food compartments whereby air contacting with said element may circulate through said ice compartment but is prevented from entering said food compartment. 80

4. In a refrigerating apparatus, the combination of a pair of food compartments separated by and sealed from a central upstanding chamber, an ice compartment located in proximity to but heat insulated from said food compartments, a metal lining for the ice compartment and a refrigerating element disposed between the food compartments in said chamber and contacting with the metal lining of said ice compartment. 100

5. A refrigerating apparatus comprising a food compartment, a metal lined ice compartment, a refrigerating element in direct contact with the lining of the ice compartment and extending in proximity to the food compartment, a wall interposed between said element and the food compartment to preclude circulation of air from said element into the food compartment and separate doors 110 for closing each of said compartments. 115

6. A refrigerating apparatus comprising a plurality of food compartments, a separate ice compartment, a refrigerating element and a chamber for containing the same vertically disposed between said food compartments sealed therefrom and in open communication with the ice compartment whereby air contacting with said element may circulate through the ice compartment and chamber but is prevented from entering the food compartment. 120

7. A refrigerating apparatus comprising a food cooling compartment, a separate ice compartment, a refrigerating element and a 125

chamber for containing the same extending a substantial distance into and sealed from the cooling compartment, said chamber being in direct communication with the ice compartment whereby air contacting with said element may circulate through the ice compartment but is prevented from entering the cooling compartment.

8. In a refrigerating apparatus, the combination of a food compartment, an ice compartment and a refrigerating element and a chamber containing the same extending a substantial distance into but sealed from said food compartment and adapted for cooling the food compartment, the interior of the ice compartment being in direct communication with the refrigerating element chamber whereby air may circulate between said element and interior of the ice compartment, said chamber extending vertically above the ice compartment.

In witness of the foregoing I affix my signature.
